US0D1047926S

(12) **United States Design Patent** (10) **Patent No.:** **US D1,047,926 S**
(45) **Date of Patent:** **** Oct. 22, 2024**

(54) **PLUG ADAPTER**

(71) Applicant: **GUANGDONG BESTEK MEDICAL DEVICES CO., LTD.**, Shenzhen (CN)

(72) Inventor: **Xinhua Xu**, Shenzhen (CN)

(73) Assignee: **GUANGDONG BESTEK MEDICAL DEVICES CO., LTD.**, Shenzhen (CN)

(**) Term: **15 Years**

(21) Appl. No.: **29/881,660**

(22) Filed: **Jan. 5, 2023**

(30) **Foreign Application Priority Data**

Aug. 26, 2022 (CN) 202230561727.2

(57) **CLAIM**

The ornamental design for a plug adapter as shown and described.

DESCRIPTION

FIG. 1 is a front perspective view of a plug adapter showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings are for the purpose of illustrating portions of the plug adapter that form no part of the claimed design.

1 Claim, 8 Drawing Sheets
